UNITED STATES PATENT OFFICE.

HARVEY C. HAYES, OF WASHINGTON, DISTRICT OF COLUMBIA.

SOUND REPRODUCER.

Application filed January 9, 1924. Serial No. 685,290.

To all whom it may concern:

Be it known that I, HARVEY C. HAYES, a citizen of the United States, and resident of Washington, District of Columbia, have invented certain new and useful Improvements in a Sound Reproducer, of which the following is a specification.

My invention relates to a means for transforming electrical energy into sound energy, and more particularly to a sound receiver or reproducer.

In order to transform electrical energy into sound energy without distortion, it becomes necessary to furnish some mechanism carrying a movable or vibrating member that will be caused to move by the fluctuating electrical current, and in such a way that the pressure fluctuations of the air caused by the vibrating movements of this member will have the same characteristics as the current causing this member to move. This requires that the movable member shall be of such a design or shall be subjected to forces in such a way that it will not break up into partial or harmonic vibrations and shall be so designed or so damped that all vibrations cease when the current fluctuations stimulating the motion cease.

These desirable conditions have been approached by the use of conical shaped diaphragms and by damping the motion of flat diaphragms over those regions where the harmonic loops occur, but usually the method of driving the diaphragm from a point or small region about its center is so favorable to the establishment of harmonics in the diaphragm that the damping required to eliminate them must be so effective that the motion of the diaphragm as a whole is greatly hindered and the device becomes very insensitive.

The tendency of a diaphragm to break up into harmonic vibrations would be almost nil if the driving force could be uniformly distributed over the whole surface instead of being concentrated at a point or small region near its center. It is evident, also, if the diaphragm could have the form of a cone so that its rigidity would tend to prevent the formation of harmonics by such small tendency as might exist, the device would come very near to giving true reproduction. And if the diaphragm could be

subjected to conditions such that it would be somewhat highly and uniformly damped over its whole surface, the reproduction would come still nearer to being perfect, especially if the diaphragm can be made to have small inertia so that the restoring forces are small.

An object of this invention is to provide a receiver having a conical shaped diaphragm with uniformly distributed driving and damping forces which will accomplish the above advantages.

With this and other objects in view the invention consists in the construction, combination and arrangement of parts as will be hereinafter described.

Referring to the accompanying drawing forming part of this specification and in which the figure illustrates a cross-sectional view of a sound receiver, 1 indicates a cylindrical member forming part of a magnetic circuit consisting of magnetic material elements 1, 2, 3, and 4, and having a coned-shaped upper portion and reduced lower portion. The reduced portion of this member seats in a ring 2 which is provided with a passageway for conductors 9. 3 is a cylindrical outer member connecting the ring 2 and a conical air-gap between 1 and 4. The magnetic circuit can be energized by a direct current carried by conductors 9 through coil 5 or the metal of the circuit can be made of magnet steel such that the magnetic flux of the circuit will be maintained after being once established. Coil 6, which is wound upon the coned surface of member 1, carries the telephonic current that is to be transferred into sound energy, and which is led to it by wires 8 passing through member 1. A thin conical shaped diaphragm, preferably made of aluminum, is flexibly suspended between 4 and the coil 6 by a flange 11 which is secured to the member 4 by screws 10.

The principle of operation of the device is as follows:

The fluctuating telephonic currents through coil 6 generate substantial eddy currents in the aluminum conical diaphragm because of close electrical coupling be'ween these elements. These eddy currents circulate about the diaphragm in a direction perpendicular to its axis, and are of uni-

form density throughout the diaphragm if the windings of coil 6 are uniformly distributed over the cone surface of member 1.

The eddy currents traversing the coned 5 part of the diaphragm pass perpendicularly through the magnetic field of the cone-shaped air-gap, and, according to the well known laws of electro-dynamics, the conductor carrying the current will at all points 10 experience a force tending to produce motion along a line perpendicular to both the current and the magnetic field, the direction along this line being determined by the direction of the current around the cone of the 15 diaphragm. And since the magnetic field is perpendicular to the surface of the diaphragm and the current is perpendicular to an element of the conical surface at all points, it follows that the forces tending to 20 move the diaphragm are at all points along an element of the conical surface.

Proper design of the magnetic path or 25 air-gap, or both, will make the magnetic field strength substantially uniform throughout the air-gap, and since the current density is practically uniform throughout the cone of the diaphragm, it follows that the forces tending to urge each particle of the conical portion of the diaphragm back and forth 30 along an element of the cone may be made substantially uniform throughout the coned portion of the diaphragm. Moreover, the force at any and every point in this part of the diaphragm can be resolved into two components, one radial to the cone and the other 35 parallel with its axis. The components parallel with the axis are all in one direction at any instant, the direction being determined by the direction of the telephonic current in coil 6 at that instant. These forces, therefore, tend to drive the diaphragm back and forth along its axis and the driving force is uniformly distributed over the conical surface of the diaphragm. This force is at all 40 45 times proportional to the strength of the magnetic field in the air-gap and to the telephonic current in coil 6.

Since the diaphragm is both pushed and pulled by the action of the telephonic current and does not depend upon restoring forces within itself for its motion, the circular flange provided for mounting the diaphragm can be made very light and flexible and under such conditions the natural resonant frequency can be made lower than that 50 55 of the sounds which the device is designed to generate. In this way resonance can be largely eliminated. But even if this were not done the device cannot be highly resonant for the reason that motion of the diaphragm is highly damped. If the diaphragm is made to vibrate either by its own inertia and restoring forces or by some other agency, the coned portion of the diaphragm 60 65 will cut across the magnetic field of the air-

gap with the result that eddy currents will be generated about the cone in such a direction as to oppose its motion. Moreover, this damping effect will be uniformly distributed over the whole conical surface of the dia- 70 phragm. This effective damping causes the diaphragm to move at all times in proportion to the driving current and to stop moving when the driving current stops.

The forces tending to move the diaphragm 75 are wholly due to the reaction of a current passing through a magnetic field and not to a variation in the strength of one or more magnetic poles. This gives the present invention two advantages: First, since its operation is independent of varying the strength of the magnetic circuit, the flux of this circuit can be kept saturated and constant and this gives the device a high power factor by confining the flux change through 80 the coil 6 to what it would be if there were no iron present. This reduces the reactance of the telephonic circuit to a small value and at the same time practically eliminates the usual losses due to hysteresis. The eddy 85 current losses are also greatly reduced for the reason that those set up in the moving member are utilized for driving this member. Second, the force driving the dia- 90 phragm is always proportional to the current through coil 6, while in most sound re- 95 producing devices of the telephonic class the force is proportional to the magnetic flux linkage between the fixed and movable parts of the magnetic circuit and this in turn is a 100 somewhat complicated function of the current through the telephonic coils and the relative position of the movable part of the magnetic circuit. As a result, the forces tending to move the diaphragm are not proportional to the current and the character- 105 110 115 120 125 istics of the generated sound waves are not strictly proportional to the characteristics of the current.

Having described my invention, I claim: 110

1. In a device of the character described the combination of a magnetic circuit having a conical air gap, a telephonic current winding uniformly disposed on one side of said gap, and a conductive cone dia- 115 phragm movably suspended between said winding and the second side of said air gap and having the angularly disposed walls thereof substantially parallel with said winding.

2. In a device of the character described the combination of a fluxed magnetic circuit having a conical air gap, a current carrying winding uniformly disposed on one side of said gap, and a conductive cone dia- 120 phragm vibrarily suspended in said gap and having the angularly disposed walls thereof substantially parallel with said winding.

3. In a device of the character described 130

the combination of a magnetic circuit having a conical air gap, a current carrying conical winding fixed in said gap, and a conductive cone diaphragm vibratory suspended in said gap and having the angularly disposed walls thereof substantially parallel with said winding.

4. In a device of the character described means for creating a conical magnetic gap, a conductive cone diaphragm vibratory suspended in said gap, and means for inducing uniformly distributed eddy currents in said diaphragm. 10

HARVEY C. HAYES.
